UNITED STATES PATENT OFFICE

WILLIAM NASH AND MONTGOMERY KENFIELD, OF MALDEN, MICHIGAN.

IMPROVED MACHINE FOR PREPARING HUSKS FOR MATTRESSES.

Specification forming part of Letters Patent No. **83,402**, dated October 27, 1868.

To all whom it may concern:

Be it known that we, WILLIAM NASH and MONTGOMERY KENFIELD, of the town of Malden, in the county of Branch and State of Michigan, have invented certain new and useful Improvements in a Machine for Preparing Corn-Husks for Making Shuck Mattresses for Beds; and the following is a full, clear, and exact description of the same, reference being had to the accompanying drawings, making a part of this specification, in which—

Figure 1 represents a side elevation of the machine, having a broken-out section of the end of the cap or cover, showing the spiral cutting-blades with the springs and feed-rollers in dotted lines. Fig. 2 shows a plan or top view of the machine with the cap or cover removed.

The object of our invention is to facilitate the manufacture of shuck mattresses and make beds of corn-husks that will be soft and pliable enough for comfort in warm weather.

Our invention consists in the construction and arrangement of mechanism for feeding in the husks and slitting them into shreds sufficiently fine for making soft mattresses and cheap comfortable beds for the warm season in hot climates.

To enable others to make and use our invention, we will describe it more fully, referring to the drawing, and to the letters marked thereon.

We make a broad flat box, A, supported on legs B B. The sides C C form the bearings for the journals for the cylinder D to run in. The cylinder D is provided with three or more rows of thin sharp cutting-knives, e e e e, set spirally in rows, working through between a series of springs, a a a, made of metal, which are secured to the bottom of the box A in the recess d, in which the lower feed-roller, E, is placed. Above the roller E is hung the top feed-roller, F, inside of the box, the journals of

which are connected to yielding springs f f, secured to the sides C C of the box A.

The feed-roller E is provided with a band-pulley, g, by which it is driven by a cross-band, h, from a corresponding pulley, G, on the rear-side end of the shaft of the knife-cylinder D, which is put in motion and operated by a pinion, I, and gear-wheel J, in which is a crank-handle, K, to turn it with, the cutting-cylinder D and springs e e e being covered over with a box, L, to protect the knives and prevent any one from getting cut or damaged by them.

It has become a well-established fact that there is nothing in use more healthy or desirable for under beds or mattresses than corn-husks, and when they are cut into fine shreds and crimped or beat up loose they make a very cool and comfortable bed for the hot season, more desirable than sea-moss or any other vegetable production, not so heating as raw cotton, and more wholesome than curled hair of reathers.

By our improved machine, as above described, the husks may be slit very finely and rapidly and nicely prepared for the purpose.

What we claim as our invention, and desire to secure by Letters Patent, is—

The arrangement and combination of the feed-rollers E and F, the spiral cutting-cylinder D, and the series of slotted springs a a a, as constructed, and operating substantially in the manner as and for the purposes herein set forth.

In testimony whereof we hereunto subscribe our names.

WILLIAM NASH.
MONTGOMERY KENFIELD.
